ELECTRIC CORD ATTACHMENT FOR IRONS

Glen A. Holland, Bronxville, N. Y., and Howard H. Schott, Greenwich, Conn., assignors to The Yale & Towne Manufacturing Company, Stamford, Conn., a corporation of Connecticut

Application July 13, 1945, Serial No. 604,828

6 Claims. (Cl. 219—25)

1

This invention relates to an electric iron, and more particularly to means for securing an electric cord to an electric iron. Even more particularly, this invention relates to that class of devices for securing an electric cord to an iron in such a manner as to make the iron readily reversible for right and left hand operation.

Devices of this type have been known in the art for quite some time, and there are several patents showing different means for obtaining the general results thus far outlined herein. Our invention contributes a considerable improvement over the prior art devices in that the electric cord is adapted for projection from the iron to one side or the other of the handle, and is also adapted to project upwardly somewhat so as to facilitate the manipulation of the iron without interference from the cord. This relationship of the cord to the iron forms one feature of our invention.

Another feature of our invention resides in the means whereby the cord is readily assembled to the handle of the iron for later assembly to the iron itself.

We have thus outlined the more important features of our invention in order that our contribution to the art may be better understood and in order that the relation of our contribution to the prior art may be better comprehended. We do believe that our contribution is a broad and valuable one and that we are entitled to patent claims that will prevent newcomers in the field from utilizing our contribution to the art with such variations in physical structure as will readily occur to those skilled in the art. Also, while we have described generally several important features of our invention, there are other important features that will be described particularly in the specification and will be claimed in the claims appended hereto.

Referring now to the drawings, Fig. 1 is a perspective view of an iron in which our invention is embodied. Fig. 2 is a perspective view of the rubber sheath and the rotating sleeve to which the electric cord is secured, and with the limiting detent shown in operative relation to the sleeve. Fig. 3 is a section taken through the handle of the iron showing the cord secured thereto and relatively to the rotating sleeve. Fig. 4 is a section of a part of the handle showing the parts of the cord securing means in exploded view. Fig. 5 is a section taken along lines 5—5 of Fig. 3. Fig. 6 is an end view of the sleeve and the parts to which it is secured, looking in the direction of the arrow 6 of Fig. 3.

2

Referring now more particularly to the drawings, reference numeral 10 indicates generally an iron relatively to which is secured a handle referred to generally by reference numeral 11.

5 This handle is preferably made of some plastic material and is formed with a grip portion 12, a forward standard 13, and a rear portion 14 that we call the rear standard. The handle 11 is formed with an opening 15 that is in communication with a chamber or hollow 16 cast within the handle as is best seen in Figs. 3 and 4.

The electric cord for our iron is designated by reference numeral 17 and comprises a pair of suitably insulated wires 18 within an insulation member 19. Those ends of the wires 18 terminating within the iron are secured by a pair of screws 20 to suitable elements, as those skilled in the art will appreciate. The other ends of the wires 18 are of course secured to a suitable type of electric plug. Between the plug and the screws 20, the cord 17 passes through a bearing sleeve 21 and a rubber sheath 22. The rubber sheath 22 is formed integrally with the sleeve 21 by being cast onto the said sleeve, and more particularly

20 about the threads 23 forming part of the said sleeve. The relationship of the sleeve 21 and the sheath 22 is such that the cord 17 will be held by the sheath at right angles to the axis of the sleeve.

25 The sleeve itself has a pair of flanges 24 and 25 between which is formed a cylindrical bearing surface 26 that is adapted to be applied to a bearing surface 27 formed on the bracket 28 cast integrally with the handle 11. It is the function 30 of the bearing surfaces 26 and 27 of the sleeve 21 and bracket 28, respectively, to mount the sleeve 21 for rotation, so as to position the sheath 22 in either its full line position of Fig. 6 or its dotted line position of Fig. 6, thereby converting the iron 35 from a left hand to a right hand iron and vice versa.

The flanges 24 and 25 function, as is best apparent from Fig. 3, to hold the sleeve against any axial movement relatively to the bracket 29. A pair of screws 30 secure a retaining plate 31 to the bracket 28 in position to hold the sleeve 21 against the bearing surface 27. The screws 30 further secure a detent member 32 in position so that its V-portion 33 may cooperate with the 40 V-notches 34 and 35 formed on flange 25 of the sleeve 21. It is of course obvious that the detent 32 will thus yieldingly retain the sleeve in either one of its opposed positions as is defined by the notches 34, 35.

45 55 In assembling the electric cord to the iron, the

cord is first passed through the sheath 22 and the sleeve 21 as is best illustrated in Fig. 4. The sleeve is then applied to the bearing surface 27 of the bracket 28 and the retainer plate 31 and detent 32 are secured in position by the screws 30 all as best illustrated in Fig. 3. The wires 18 within the chamber or hollow 16 are then secured in proper operating relation by screws 20, while the outer ends of the wires 18 within the conductor 17 may be secured to a terminal plug as is usual in this art. The electric cord is now completely assembled to the handle and is ready for application to the iron. It is of course obvious that the cord will move readily with the sheath 22 and the sleeve 21 to convert the iron from a right hand to a left hand and vice versa, as may be found desirable. It will also be appreciated that in either of its handed positions the electric cord will extend outwardly and upwardly from the handle of the operator on the grip 12, and thereby facilitate the manipulation of the iron.

We now claim:

1. In an iron of the class described, a handle having a grip portion and a hollowed standard portion formed with a large bottom opening, said handle having a relatively small opening through its upper exterior surface just rearwardly of the grip portion and leading to the hollow of said standard, an electric cord for said iron, a sleeve for said cord, a bearing surface for said sleeve formed on a surface inside said hollowed portion of the standard whereby said sleeve may be inserted with said cord into said hollowed standard through said bottom opening and the sleeve applied to the said bearing surface as the electric cord is passed through the small opening at substantially right angles to that portion of the cord within said sleeve, and retainer means for holding said sleeve on said bearing surface for rotation relatively thereto.

2. In an iron of the class described, a handle having a grip portion and a hollowed standard portion having a large bottom opening, said handle having a relatively small opening through its upper exterior surface just rearwardly of the grip portion and leading to the hollow of said standard, an electric cord for said iron, a sleeve for said cord, a bearing surface for said sleeve formed on a surface inside said hollowed portion of the standard whereby said sleeve may be inserted with said cord into said hollowed standard through said bottom opening and the sleeve applied to the said bearing surface as the electric cord is passed upwardly through the small opening at substantially right angles to that portion of the cord within said sleeve, and said bearing surface being positioned for rotation of said sleeve on an axis substantially at right angles to that portion of the cord moving in said small opening.

3. In an iron of the class described, a handle having a grip portion and a hollowed standard portion having a large bottom opening, said handle having a relatively small opening through its upper exterior surface just rearwardly of the grip portion and leading to the hollow of said standard, an electric cord for said iron, a sleeve for said cord, a bearing surface for said sleeve formed on a surface inside said hollowed portion of the standard whereby said sleeve may be inserted with said cord into said hollowed standard

through said bottom opening and the sleeve applied to the said bearing surface as the electric cord is passed through the small opening, said bearing surface being positioned for rotation of said sleeve about substantially a horizontal axis in the normal operating position of said iron.

4. In an iron of the class described, a handle having a grip portion and a hollowed standard portion having a large bottom opening, said handle having a relatively small opening through its upper exterior surface just rearwardly of the grip portion and leading to the hollow of said standard, an electric cord for said iron, a sleeve for said cord, and a bearing surface for said sleeve formed on a surface inside said hollowed portion of the standard whereby said sleeve may be inserted with said cord into said hollowed standard through said bottom opening and the sleeve applied to the said bearing surface as the electric cord is passed through the small opening.

5. In an iron of the class described, a handle having a grip portion and a hollowed standard portion having a large bottom opening, said handle having a relatively small opening through its upper exterior surface and leading to the hollow of said standard, an electric cord for said iron, a sleeve for said cord, a bearing surface for said sleeve formed on a surface inside said hollowed portion of the standard and integral therewith whereby said sleeve may be inserted with said cord into said hollowed standard through said bottom opening and the sleeve applied to the said bearing surface as the electric cord is passed through the small opening, and a pair of flanges on said sleeve overlying the end surfaces of said bearing surface for preventing endwise movement of said sleeve relatively to said bearing surface.

6. In an iron of the class described, a handle having a grip portion and a hollowed standard portion, said handle having a relatively small opening through its upper exterior surface leading to the hollow of said standard, an electric cord for said iron, a sleeve for said cord, a bearing surface for said sleeve formed on a surface inside said hollowed portion of the standard and integral therewith whereby said sleeve may be applied to the said bearing surface as the electric cord is passed through the opening at substantially right angles to that portion of the cord within said sleeve, a pair of flanges on said sleeve overlying the ends of said bearing surface for preventing endwise movement of said sleeve, and a retainer plate secured to said standard for holding said sleeve against said bearing surface.
